CONTINUOUS CASTING AND ROLLING
OF METALSJohn C. Bongiovanni, University Heights, Ohio
(221 Elmtree Road, New Kensington, Pa.)
Filed Oct. 28, 1960, Ser. No. 65,818
7 Claims. (Cl. 29—33)

This is a continuation-in-part of my application Serial No. 833,538, filed August 13, 1959, now Patent No. 3,146,525, issued September 1, 1964.

The present invention is concerned with the direct production of sheet or strip or bar stock from metals in a molten condition. Specifically the present invention is concerned with method and apparatus whereby a molten metal may be continuously cast and reduced directly to a sheet or strip or bar form.

In broad terms, the present invention, insofar as method is concerned, is directed to the formation of a molten body of metal of desired composition, continuously casting the same into an endless slab or ingot form, rectangular or round in cross section, and rolling or reducing the same while yet in a hot state for example into a continuous strip of desired gauge, the strip being then either cut into desired lengths of sheet or plate, or alternatively coiled and severed at desired coiled lengths. The invention will be discussed in terms of sheet or strip production with the metal as cast having a rectangular cross section, but a round section may be used; and also other product sections may be produced as later described.

With respect to the mill with which the invention is concerned, there is involved the combination of a direct casting apparatus—of which several types are known to the art—for producing from continuously supplied molten metal a vertically descending slab in continuous form of approximately the desired final width of the strip or sheet stock; the molten metal being solidified in passing through the mold characteristic of such apparatus and partially cooled by water sprays or jets immediately beneath the mold, two sets of pinch rolls spaced below the nozzle serving not only for control of the casting speed for maintenance of the slab as a moving plug in the casting mold and providing a reaction or anchor means for tension to which the slab is subjected in the heavy reduction; and a vertically reciprocating roller type mill for the heavy major reduction of the metal.

In the combination a vertically reciprocating pair of rolls on each downward stroke engage the slab and are cammed toward each other to produce a complete reduction of the hot cast slab to desired thickness; while on an upward stroke the rolls, first separated into a non-working relation for slab clearance, are returned into working spacing for re-engagement with the slab at about the top of the stroke. The main rolling portion of the apparatus—located directly below the casting mold so that the plane or centerline of movement of the metal from the mold, through pinch rolls and through the operating path of the mill rolls, is in a substantially vertical plane—is in effect a vertically disposed hot rolling mill; and the mechanism thereof generally of the type disclosed in the Krause Patent 2,161,064 or 2,161,065.

With this overall arrangement the energy required for the metal reduction is not absorbed from a power source only during the downward working stroke, for there is a

2

considerable potential energy available for metal reduction in any practical mill at the beginning of any downward working stroke due to the elevation of the mass of the reciprocating rolls and their mounting or carriage structure; and, therefore, such potential energy is absorbed by or fed into the reciprocating system also on the non-working upward stroke of the rolls. Hence, the power requirements in the motor or prime mover for the rolling mill, and also the structural strength needed in elements of the power transmission system for the rolls, are lower for example than in prior horizontal Krause type mills. Also with vertical movement of a roll carriage in contrast with horizontal movement frictional losses in the moving system can be greatly reduced furthering economy of energy requirements, and also thereby helping to reduce the structural and power motor requirements.

The reduction of a continuously cast and endless slab further eliminates the waste of prior mills operating horizontally to reduce successive billets or slabs and resulting in butts or stub ends which cannot go through the mill. Also the vertical casting results in better temperature control of the metal in solidifying and thereafter in passing to the reduction region.

A greatly advantageous characteristic of the invention is the fact that there is achieved a practically instantaneous reduction, on the order of 90% as a minimum, in thickness in an effectively hot rolling operation thereby changing the metal structure from an as-cast predominantly large or average open grain to a uniformly fine grain, with excellent homogenizing effect, and a consequent great increase in tensile strengths.

In addition to the above-described features, there are here disclosed as located beneath the rolling mill a very economic means for cutting off and handling the finished strip, either in coil form or in flat sheets. For this purpose there is located immediately beneath the mill a power-operated shears for cutting the continuous product strip at appropriate points. Below the shears there are located, as alternative means of handling the finished strip, first a coiling apparatus for turning the strip length into say loose coil form; and therebeneath an "up-ender" device, a tilting sheet receiving and discharging mechanism. From the coiler there is provided a suitable coil ramp or other conveying means advantageously gravitational, whereby the final coils are directed to a point of loading or further handling. On the other hand, where the product is to be in sheet or plate form, the up-ender or tilting receiver accepting each length of material cut from the continuous strip in its vertically descending path is thereafter turned toward a disposition somewhat beyond horizontal to discharge the severed sheet onto a conveying system—again advantageously gravitational—for carrying the same to a final point of loading or other disposition; as for example to a point where the same are stacked and baled or palletized.

The general object of the present invention is then the provision of an improved method and apparatus for the production of a continuous metal form from molten metal. Another object is the provision of method and apparatus for direct casting of metal into a continuous ingot and reducing the slab to strip, sheet, plate or "bar" form. A still further object is the provision of a method and apparatus for achieving a low cost conversion of merchant metal or molten metal to strip, sheet, plate or bar form,

particularly non-ferrous metals such as copper and aluminum and alloys thereof, but also ferrous metals.

Other object and advantages of the invention will appear from the following description and the drawings wherein:

FIG. 1 and FIG. 1a present in side elevation the relations of the principal parts of a plant or mill for carrying out the method or process of the present invention; certain parts being omitted in FIG. 1, and others being represented in generalized or outline form in FIG. 1a for overall clarity;

FIG. 2 is a somewhat enlarged side view of the principal part of the rolling mill proper;

FIG. 3 is a front view corresponding to FIG. 2;

FIG. 4 is a vertical sectional view taken generally as indicated by the lines 4—4 in FIG. 3 through the reciprocating housing and roll carriage contained therein;

FIG. 5 is an irregular transverse sectional view taken, however, substantially as indicated by the line 5—5 in FIGS. 3 and 4;

FIGS. 6 and 7 are front and side views respectively of the roll carriage frame;

FIG. 8 is a fragmentary detail of a roll camming wedge block adjustment means;

FIG. 9 is a schematic representation of hydraulic and electric control circuitry for the rolling apparatus;

FIG. 10 is a schematic representation of the positioning in a mill of the type described of brushes operating at various locations on the slab, pinch rolls, working rolls and product;

FIG. 11 is a fragmentary vertical section showing the mounting for a work roll cleaning oscillatory type brush;

FIG. 12 is a further fragmentary section taken as indicated by the line 12—12 in FIG. 11;

FIGS. 13a, 13b and 13c show cross sections of rod or bar stocks by way of example of other forms which may be rolled; and

FIG. 14 shows the general manner in which the form of the rolls and of the cam used are changed to produce such different stocks, here specifically that of FIG. 13c.

An overall view of a vertical hot rolling mill for production of strip, plate or sheet stock from molten metal according to the present invention is presented by FIGS. 1, 1a. At a top floor of the mill, there is a furnace F for melting or holding in molten state metal continually poured from the nozzle thereof to be cast through a die-like direct casting mold D into a slab or billet-like continuous piece B; and immediately below D there are disposed the controlled continuous water-spray jets or cooling apparatus W, for partially cooling the slab and solidifying the metal while yet in the mold D. The mold may itself be water cooled. Below W are arranged in tandem two pair of pinch rolls, such as a conventional Horsburg and Scott pinch roll drive, driven at a selected rate to control the rate of casting or production of the slab at D, the rolls being located immediately below and in alignment with D and W. In general, the furnace or other means continually pouring metal to the mold producing a slab of desired thickness and width, the cooling apparatus and the pinch rolls may be similar to those well known now in the art for direct casting processes. By way of example, an aluminum slab B may have dimensions on the order of 4 by 12 inches in leaving the mold. Where $\frac{1}{4}$ inch by 12 inch strip is to be produced, a round billet could be cast as later noted.

For continuous reduction of the slab B to a plate, sheet or strip form, there is further provided on the next lower floor the reduction or rolling mill M located vertically below the pinch rolls P, the mill M effecting the major reduction of the slab thickness. Insofar as the reduction rolling apparatus itself is concerned, and its manner of operation, it may be said to be generally similar to that of the Krause Patent 2,161,064, or 2,161,065.

For handling the strip metal produced in the mill M, there are arranged there-beneath (see FIG. 1a) on a lower floor a shear device S, such as a Halden type shear, and for manipulation of the sheared product a three-roll up-coiler apparatus C into which the strip-like product may be directed and there formed into a loose coil; here again the apparatus being similar to prior well-known forms. With the coiling apparatus, for transport or conveyance of a finished coil of desired length away from the mill, there is also associated a conveying device such as an inclined guide ramp for directing the coils for example to a loading dock. Below the coiler, as an alternately available means of handling the product, there is disclosed a plate or sheet receiver mechanism or "up-ender" T, a roller lined elongated frame which, from a position vertically aligned with the path of the strip product to receive the same as it is cut off at appropriate lengths in sheet or plate form by the shears, is tiltable to a position slightly beyond horizontal for gravity discharge of the received plate to a conveying system carrying the same to a baling area or loading dock.

The mill M has a sturdy upright frame comprised of four rigidly parallel spaced and anchored vertical columns 10, such as structural steel I-beams with transverse spacers 10a, wherein a heavy integrally cast hollow housing H is guided for vertical reciprocation by four guide roller assemblies 11 at each corner of the housing. A mill power and driving system comprises a prime mover 12, such as a three-phase high voltage heavy duty motor; a pair of reduction gearing units 13, 13 on opposite sides of the mill with input shafts coupled by a cross shaft 14, and (at the left of FIG. 3) the motor being also connected to the input on one side of the unit 13 by a suitable coupling 15. The output shafts of the reduction gearing units carry respective suitably counter-balanced fly wheels 17, each having a crank pin 18 connected through a connecting rod 19 with the housing H through a wrist pin 20 journalled in bearings inserted in the housing. Suitable thrust washers are disposed between the inner faces of the wrist pin mounting formations of the housing and the adjacent faces of the connecting rod 19.

The roller guide units 11 each comprise a spacer block or mounting bar 21 secured on a respective column 10 and having rotatably mounted on adjacent faces series of vertically equispaced rollers 22, 23. The rollers of one series are staggered relative to those of the other series and radially project beyond the face of the bar mounting the other series, so that each corner of the housing is embraced and guided by rollers 22, 23, bearing on respective vertical finished areas running from top to bottom of the housing.

The roll carriage RC is an elongated generally open frame (see FIGS. 6 and 7) here shown as formed by two pairs of joined corner angle irons 40-l, 40-r (left or right pair in FIGS. 5 and 6) connected by suitable cross struts or braces, such as 40a, 41a and 40b, 41b at the top and toward the bottom respectively, and 40c, 41c and 40d, 41d near the middle of the carriage, the front and back sides between respective members 40-l and 40-r being open and members 40a-d being set inwardly therefrom for clearance relative to the hereinafter described cam plates 55. The carriage also is guided and embraced at each corner on finished areas by bearing strip pairs 43 and 44 secured at corners in the hollow central space of the housing, there being also a vertical inward slot at each inside corner of the housing for accommodation of a corresponding vertical carriage rack 32. As may be noted in FIG. 4, 6 and 8 the racks 32 are carried on the lower end of the corner angles 40-l and 40-r which extend below the housing H even when the latter is in its uppermost position, at which time the carriage RC is in its lowermost position relative to the housing H, as in FIG. 4.

For effecting synchronized reciprocation of the roll carriage relative to the housing during reciprocation of the latter on the mill frame four rack and pinion mech-

anisms are provided. Each comprises a vertical fixed rack 26 mounted outboard of a roller support bar 21 and meshed with pinion 27 carried on a transverse shaft within a gearing housing or frame 28, bolted or otherwise secured on a bottom surface of the main casting of the housing H. The pinion 27 is meshed in turn with a gear 29 carried on shaft 30 commonly with and rotatable with the pinion 31 meshing with a corresponding carriage rack 32. The pitch diameter of 29 is twice that of 27 and 31, whereby the movement of the roll carriage is half that of the housing H relative to the mill frame.

At opposite sides of the roll carriage RC, in the region between the respective middle vertically paired cross braces 41c, 41c and 40d, 40d there are formed corresponding parallel transverse slideways 48 for receiving in each a pair of opposed sliding bearing chock 49a, 49b for the roll neck bearings. Each chock is of a generally rectangular block form and has a large central aperture with a sleeve bearing journaling the roll neck of a corresponding roll R. The bearing chocks 49a for one working roll, at their upper and lower ends, each have blind bores or holes formed in parallel fashion to receive the ends of vertically spaced paired single acting hydraulic cylinder units 51, with pistons 52 bearing against opposed shoulders on a corresponding one of the facing bearing blocks 49b supporting the other working roll. The cylinder units 51 hereinafter called balancing cylinders are constantly pressurized to extend the same in a dash-pot cylinder arrangement, and normally tend to spread the rolls from each other. Accordingly, each chock block 49a is provided with suitable passageways for hydraulic fluid leading to the balancing cylinders 51 from flexible hose connections pressurized by hydraulic fluid supply system. There is a suitably sized window between the frame members opening into the slideway at each side of the frame, and also in the housing, which are alignable for removal and insertion of the rolls and chocks for servicing the assembled mill.

At the front and back sides (top and bottom of FIG. 5) of the vertical central opening of the housing H which accommodates the roll carriage, there are like opposed vertically extending channels or recesses wherein are mounted the cam plates 55 by bolts 55b to be vertically fixed relative to the housing H by thrust plates 55c but shiftable along bolts 55b toward and away from each other, and each cooperating with a respective one of the rolls R riding thereon. The shape (see FIG. 4) and function of the cam plates are hereinafter set forth. The cam plates are urged outwardly by compression springs interposed on each bolt between a nut thereon and the housing. Certain control and shifting means for the respective cam plates are also mounted behind the latter in the channels, including an elongated rather thin wedge plate 56 with its outer flat face bearing upon a corresponding flat surface 54a of the channel; and a larger hollow wedge or taper block 58 having sloping face 58a complementary to and bearing on the inner sloping face 56a of the wedge 56 and an inner flat face in contact with the flat outer face of the cam plate 55.

It will be noted that the widths of both 56 and 58 are less than the corresponding dimension of the channel or recess whereby shifting of 56 and 58 from one side to the other (i.e., from left to right as viewed in FIG. 5) is permitted. The large taper block 58 has a central recess 58c (see FIG. 8) with parallel vertical walls between which there is received a closely fitting nut block 60. A power driven lead or adjusting screw 61 engaged in block 60, journalled at its inner end by a sleeve bearing 61a in one wall of the recess 54, extends through and is axially fixed in a bearinged aperture 61b in the opposite wall by retainers 61c for coupling at 62 to the reversible drive motor and reduction gearing unit 63 bolted to the right side of the housing H.

The taper block 58 is transversely slotted in the region of the screw 61 to permit not only axial shifting of the

block as it is carried by the nut 60 but also an inward and outward shifting as it is moved along the taper of the opposed small block 56. The blocks 56 and 58 are also slotted transversely at top and bottom for the cam plate bolts 55b therethrough to permit the in-and-out movement of the taper or wedge blocks.

On the side of the housing H opposite the location of the motor 63 a double acting hydraulic piston unit 66, as a hydraulic reciprocating motor for a corresponding block 56, is mounted for reciprocation in direction transversely of the housing, that is, parallel to the direction of the lead screw 60 and to the axes of the rolls, and has its piston coupled to a stud 68 threaded into the broad side of the taper block.

Considering now the situation of FIG. 5, it is seen that one extreme working setting, a maximum spacing of the two cam plates from each other, and hence a maximum spacing of the rolls for any given position longitudinally of the cam plates is achieved under the conditions there appearing with 56 and 58 at the extreme right. However, upon withdrawal to the left of each block 56, as in FIG. 8, the blocks 58 and cam plates 55 actually follow so that the rolls immediately separate to clear the slab by action of balancing cylinders 51 upon the roll bearing chocks as in fact is intended to happen at the end of the downward housing or rolling stroke. However, upon simultaneous return of the two plates 56 by extending force of the units 66, the cam plates are then urged to return to the position of FIG. 5. However, when the power screws drive the blocks 58 to the left, the opposed tapers of 56 and 58 cause the blocks 58 and hence the cam plates 55 to move inwardly, thereby narrowing the roll spacing. Since the whole structure of the housing H, carriage RC and the other reciprocating components are in general symmetrical about the centerplane of the roll carriage, i.e., centerplane of the continuously cast slab and the product strip, the inward feed or retraction of the blocks 58 should normally be equal; and also the release and return of the same by operation of cylinders 66 should take place simultaneously.

Considering now a typical operation for conversion of aluminum to one-fourth inch plate 12 inches wide, the casting mold or die D of the furnace would be sized 4 by 12 inches to produce a hot billet of corresponding cross-sectional dimensions. With the slab entering the pinch rolls at a four inch thickness, and as a typical operating temperature at about 850° F., approximately a five percent reduction is effected at the pinch rolls. Therefore, the slab thickness would be 3.8 inches on entering the mill proper. Rolls, each six inches in diameter and sixteen inches long in the roll body, would be typically used in the roll carriage. With a 44 inch stroke of the housing, there is effected a corresponding relative upward movement of twenty-two inches of the roll carriage relative to the roll housing or a movement of only twenty-two inches of the carriage downward relative to the mill frame, by virtue of the rack and pinion gearing previously described. On the downward or working stroke of the mill this relative movement of the roll carriage relative to the housing is in a reverse direction, that is, there is a 22 inch vertically upward displacement of the roll carriage relative to the housing; in other words, on the downward stroke of the housing this travel being subtracted from the total travel of the housing, the carriage is carried downward only 22 inches.

In FIG. 4 the relative position of the elements at the extreme upward position of the housing is shown in full lines; while the corresponding relation of the elements at the extreme downward position at the bottom of the stroke is shown in dashed outline for certain elements such as the rolls and cam plates.

Consider now a typical installation utilizing a 200 horse power motor, rated for 1750 r.p.m. at 440 volts, three-phase 60 cycle power with 8 foot connecting rods, and a total mass of the reciprocating housing and all elements

carried thereby of approximately 10,000 lbs., and 60 strokes per minute for the working rate. With a four inch thick "as-cast" slab reduced to 3.8 inches in the pinch rolls feeding at a rate of $\frac{1}{8}$ inch for each working stroke cycle, in other words, about 1.9 feet per minute at 850° F. and with an elongation factor of 15.2 in the rolling, there is obtainable a delivery of 5.7 inches of the $\frac{1}{4}$ inch thick strip or plate per stroke or about 28.5 feet per minute or 1710 feet per hour. This would then represent a conversion of about 6480 lbs. per hour of aluminum.

Returning again to FIG. 4, the system is shown just as a downward stroke is about to begin. The cylinders 66 are under pressure to drive the wedges 56 inward and thereby to bring the cam plates to their fixed spacing predetermined by the adjustment of the system. As the housing starts downwardly, with the carriage lagging, the cam plates "over-run" the descending rolls R, so that sloping cam surfaces in engagement with the rolls not only rotate the rolls to cause the adjacent roll surface to move in an upward direction, but also urge the rolls inwardly. Hence, as the roll carriage descends, the rolls are squeezed inwardly, each "biting" into the metal and carrying or drawing downward a crest of metal on opposite sides of the slab. Over approximately the first half of the downward stroke, say 14 inches of roll descent, the rolls are being brought together. At about one-half of the downward stroke the rolls have reached the end of the inward cam slopes and there encounter straight parallel cam faces, and accordingly, over nearly the entire remainder of the stroke, the roll spacing is held constant at the actual spacing required by the thickness in the finished product. In this latter portion of the stroke, then, "crests" of metal advanced in the bite are rolled out into flat sheet form, the rolls continuing down even after the sheet has actually been formed in flat shape for a slight over-rolling portion of the stroke which may overlap say an inch or so of metal finished on the preceding stroke, to give a desired finish and flatness to the product. The tandem pinch rolls, conventionally synchronous motor driven through a very high gear reduction, restrain the slab to provide tension reaction to the downwardly applied forces of the rolls during the downward working stroke, permitting only the slab advance corresponding to the established casting rate and feed to which the pinch roll drive is set.

Just before the end of the stroke is reached, the cylinders 66 are actuated to retract the same and release the cam plates, and also as may be noted from FIG. 4, a very slight outward taper or cam relief is encountered by each roll; so that as the stroke is completed, a slight outward or roll-separating movement is permitted under the action of the balancing cylinders. Thus, even before the downward stroke is quite completed, the rolls are actually released from their rolling engagement with the finished sheet portion, so that the normal slab feed is not impeded. During the upward or return stroke, though the housing and cam plates actually will be overtaking the carriage and rolls, since the cam plates are spread and free, the rolls may pass therebetween without interference with the finished sheet metal. By the time the rolls would be encountering the tapered end of the partially reduced slab portion, the receding outward cam slopes are passing the rolls permitting roll clearance with the increasing width of the tapered slab end. Just as the carriage is approaching the top of its stroke, say one inch from the top, control means causes the cylinders 66 again to be pressurized for extension to drive the wedge plates 56 inwardly, thereby again restoring the cam plates to the original proper working spacing. The rolling cycle then begins again, in the meanwhile the slab or billet having continuously moved down by $\frac{1}{8}$ of an inch from the position which it had at the beginning of the preceding working stroke.

In the aforescribed apparatus, the roll carriage, rolls and housing, along with the auxiliary equipment carried thereby such as the hydraulic pistons for the wedges and also the adjusting motors, represent a large moving mass elevated during the upward non-working stroke and thereby require a certain power input, not at that time used for metal reducing work. The elevation of this mass represents an increased potential energy of the system which reaches its maximum, of course, at the top of the upward stroke. As the downward stroke begins, this potential energy then becomes available as part of the working system expending energy upon the metal being worked. This accordingly lessens in some degree the load upon the driving system. In other words, there is an absorption of energy during the non-working stroke, that portion of the energy then being recoverable during the working stroke. Hence, the otherwise wide fluctuations in power demand at the input point are considerably minimized in contrast with a horizontal reciprocating mill. This then represents first a desirable general operation condition; secondly by virtue of the fact that the power demand is minimized for the working stroke, a smaller or lighter construction is possible in many of the working elements of the drive system. Furthermore, the very drive motor and other drive equipment are themselves reduced in size.

A generally conventional pressurized hydraulic system and components may be used to keep the balancing cylinders 51 pressurized continuously and to operate the double acting cylinders 66 to move the taper plates or blocks 56 in and out at the stated appropriate points in each full cycle of housing reciprocation. Such a system, as schematically presented in FIG. 9, includes an electric motor driven pump 80 delivering fluid from a reservoir 81 through an adjustable pressure regulator 82 with relief valve, through flexible hoses to the cylinders 51; and also through a regulator and relief valve 82a to a two-way control valve 83, which selectively applies fluid under pressure to the outer ends of the cylinders 66 while opening the other ends to a reservoir return line for driving blocks 56 inward at one setting, and reverses the cylinder connections to withdraw the blocks on the other setting. The entire hydraulic supply system may be mounted on the moving housing with the pump motor energized through flexible electric cables, or alternatively the pump may be fixed, independent of the housing to which flexible hydraulic lines or hoses are run.

The control valve may be a solenoidally operated type shifted by solenoid 83a from one setting to the other, under the control of single control switch 84, which is tripped or cammed to opposite settings by a set of spaced lugs 85, 86, the switch and lug set being on respective relatively moving members X, Y of which one is fixed, as the mill frame, and the other is the reciprocating housing. The lugs 85, 86 for example, may be pivoted but spring biased against a stop so that each may engage an actuating element of the switch to trip the same near a respective stroke extreme, but slip past the switch in moving in the opposite direction. On the other hand, the control valve may be mechanically actuated or tripped to one or the other setting (at the times previously described for each cycle) by encountering vertically spaced dogs or lugs near opposite ends of the housing strokes, similar to 85, 86.

With the conditions of billet feed, stroke lengths and delivery previously stated for operations on aluminum the roll supporting cam surfaces on a cam plate would have longitudinal dimensions, that is, as projected on a longitudinal line, as follows: a sloped surface of about seven and one-half degrees, 13.5 inches of the length; a straight portion of 7.1 inches, with 5.7 inches thereof allotted to "delivery" or rolling out an accumulated "bite" or crest and 1.4 inches for over-roll of metal finished on a previous stroke; and a sharply sloped or "release" portion, of $1\frac{1}{2}$ inches of the length. With one set of such cam plates as used for $\frac{1}{4}$ inch thick product obtained in the approx-

imately 16 to 1 reduction from a four inch billet, a product range of $\frac{3}{16}$ to $\frac{3}{8}$ inches is practical from the stated size of billet. However, were it desired to hot roll with a greater reduction say from 4 inches to $\frac{1}{8}$ inch, the billet feed rate would preferably be reduced and the cam slope increased.

With the previously described cam plates and the same feed rates, a 2 inch billet thickness would be preferred to produce $\frac{1}{8}$ inch product thickness, representing the reduction ratio for which the cams were specifically designed.

Generally, it may be said that the common metals of ductile character or capable of normal hot rolling are susceptible to operations as here contemplated, excepting of course certain special alloys thereof, and the same cam plates and billet size (therefore direct casting mold) may be used therewith as for aluminum by varying the rate of billet feed and the final thickness produced. Of course the temperature of the billet in arriving at the reciprocating rolls is selected according to the hot rolling temperature requirements of the particular metal, e.g. 2000-2200° F. for a 1020 or mild steel; 1800° for copper. Even for these metals, where the same reduction ratio of approximately 16 to 1 is used as first described for aluminum, about the same cam configuration and feed would be used, the specific energy requirements merely demanding varied power.

The temperature of the metal actually being cast into the mold will, as well known to the art, depend upon the specific metal composition and mold environment; for example with various aluminum alloys requiring temperatures over a range easily as broad as 1200°-1500° F.

In a schematic fashion, FIG. 10 shows disposed on opposite sides of the path of billet travel a pair of rotationally driven wire brushes 109 disposed below the location of the cooling water spray system and above the pinch rolls P, for the purpose of cleaning the slab of any scale or other adherent debris; two pairs of rotary cleaning brushes 101 for the pinch rolls P each contacting a respective roll substantially diametrically opposite the point of roll contact with the slab; two pairs of slab-cleaning rotary brushes 102 and 103 respectively below the pinch roll and below the range of movement of the working roll carriage. As various type mountings and drives for these rotary bristle brushes are known to the art they are no further described here.

More importantly, for cleaning the working rolls and preventing the same from going out of correct effective shape by accumulation of scale or the like, these rolls are each provided with a bristle brush longitudinally oscillated parallel to the roll axis. More usually the bristle brushes operating on the slab are wire bristle brushes, while those for cleaning the various rolls are comprised of natural organic or synthetic plastic bristles for protection of roll finish, though at times metal brushes may be used.

One suitable form of mounting for the oscillating brushes 104 within the roll carriage is shown in the fragmentary views of FIGS. 11 and 12 of one brush mounting. The elongated brush 104 is secured in a pair of spaced clamps 105 each having its base slidably mounted on a respective pin 106 secured on a slide block 107. The slide blocks 107 (see FIG. 12) are mounted below, and for oscillation parallel to, the corresponding roll by vertically spaced parallel rods 108 and 109 having ends respectively fixed in and slidably supported at opposite sides of the roll carriage frame; the blocks being slidable on fixed rod 108 and secured in fixed parallel spaced relation on slideable rod 109.

To oscillate the blocks 107 and hence the brush 104, depending inclined cams 111, 112 are secured to the vertically reciprocating housing H in such position as to be contacted by respective opposite rounded ends of the rod 109, so that as the roll carriage itself reciprocates vertically in the housing, the rod 109 is cammed endwise

in opposite direction on up and downwardly carriage movement by the correspondingly formed surfaces of the cam plates.

The brush clamps 105 are slidably mounted on the respective parallel pins 106 so that they may follow the rolls in and out relative to the slab to maintain cleaning contact therewith; and accordingly means must be provided to move each brush along with its roll, while permitting the brush itself to oscillate endwise. One means for this purpose (see FIG. 12) is the use at the end of each brush of a short channel shaped brush guide 114 secured to the outer end of the adjacent bearing chock as at 49b and disposed in the general orientation of clamp 105 to embrace the corresponding brush end in slidable relation.

In place of the use of a mold with a rectangular opening, a mold may be used having a circular discharge opening for casting a round billet. This may be desirable in some instances from cost considerations inasmuch as round molds for direct casting are more readily available as standard items, and also from an operational viewpoint. Where four inch strip, for example, is the desired product, a four inch diameter round billet would be cast.

Other product forms that may be produced by the method and apparatus of this invention are shown by way of example in FIGS. 13a where 130, 130 designates the cross section of a pair of square rods which are rolled in continuous length; in 13b, where 131, 131 designate the cross sections of a pair of round rods or bars which may be rolled in continuous lengths; and in FIG. 13c, where 132 designates the cross section of a bar form in effect comprised of two opposed outwardly divergent roughly wedge shaped or triangular portions 132L, 132R merged or joined at their apical regions, providing a continuously rolled stock, which may be vertically longitudinally slit at the central narrowed region to provide two wedge shaped bars suitable for use, for example, in production of commutator segments.

The roll form must of course be changed from the cylindrical form used in production of plate or strip stock to a contoured roll form of such shape that when the opposed working rolls are at their position of closest approach to each other in the working stroke, the intersections of the proximate surfaces of the two rolls with a plane through the roll axes defines or is substantially identical with the shape of the opposite sides of the desired product. Thus in FIG. 13a the rolls have cooperating opposed circumferential grooves 135 of right angle cross section; while in FIG. 13b the grooves 136 have a semi-circular cross section. For the product indicated by 13c, the rolls will have the form shown in FIG. 14 where, beginning at a region spaced inward from each end, a roll tapers or diverges outwardly toward the middle of the roll.

Furthermore with change in the roll form it may be necessary to accommodate the transverse shape of the cam plates to the shape of the rolls, as indicated also in FIG. 14 where the cam plates 55 have a shallow recess 140, triangular in cross section extending longitudinally to the inclined and straight portions of a cam throughout its length, to accommodate the circumferential central bulge produced on the roll by the outwardly tapering portions 137, 137, while the opposite side marginal portions of the cam plate face 141, 141 may retain the same flat form disclosed for the cam plates where flat stock is being rolled, to support the cylindrical end portions of the roll face. The recess 140 may be of such shape that it merely provides clearance with respect to the roll bulge or it may actually support the central part of the roll, as may be required by working stresses produced under particular operating conditions. Where the roll form is varied from a cylindrical shape merely by circumferential grooves and the remaining portions of the interrupted cylindrical surface provide adequate bearing surface, the straight and inclined portions of the cam working face may be trans-

versely flat, as would be the case for the roll forms used in FIGS. 13a or 13b.

It will be noted that the form of the product bar of FIG. 13c (see also FIG. 14) is such that the loads imposed upon the rolls are balanced along the roll axis, since the product form is symmetrical about a vertical longitudinal central plane; and for a like purpose of balancing stress or loads in FIGS. 13a and 13b the rolls are grooved to produce two square elements or two round elements from the continuously cast billet or bar, which in all three of the FIGURES 13a, b and c is round in cross section as indicated by the dashed circle 145 in each case.

I claim:

1. A mill for the continuous conversion of metal into a rolled form from molten metal comprising: a direct casting mold for producing a moving straight hot billet from molten metal, billet cooling means located adjacent said mold for maintaining the metal in solid billet form as it leaves the mold, constant speed power-driven tandem pinch roll means engaging said billet on the side of said cooling means remote from the mold to control the rate of delivery of said billet from the mold, vertically reciprocating cooperating paired roll means adapted to engage therebetween successive increments of the billet length and to move toward each other to a predetermined spacing during a first portion of each working stroke away from the mold and thereafter to be maintained at said spacing for substantially the remainder of the stroke, and means to separate said rolls during the return stroke to a spacing exceeding the thickness of the billet as delivered from said pinch roll means.

2. A mill for the continuous conversion of metal into a rolled form from molten metal comprising: a direct casting mold for producing a vertically descending hot billet from molten metal, billet cooling means located adjacently below said mold for maintaining the metal in solid hot billet form as it leaves the mold, constant speed tandem pinch roll means engaging said billet below said cooling means to control the rate of descent of said billet from the mold, vertically reciprocating cooperating paired roll means adapted to engage therebetween successive increments of the billet length and to move toward each other to a predetermined spacing during a first portion of each working downward stroke and thereafter to be maintained at said spacing for substantially the remainder of the stroke, and means to separate said rolls during the return stroke to a spacing exceeding the thickness of the billet as delivered from said pinch roll means.

3. A mill as described in claim 2, including means for cleaning said roll means.

4. A mill as described in claim 3, including means for cleaning said billet and the product.

5. A mill for the continuous conversion of metal into a rolled form from molten metal comprising: means for producing a vertically descending hot billet directly from molten metal, constant speed tandem pinch roll means engaging said billet below the first said means to determine a delivery rate of said billet, a rigid frame and a housing mounted and guided thereon for vertical reciprocation, means for reciprocating the housing, a roll carriage vertically guided in said housing with said billet extending therethrough, vertical racks on the frame and carriage and gear means meshing with said racks for reciprocating the carriage in lagging relation to the housing, a pair of horizontally spaced horizontal rolls mounted in said carriage on opposite sides of the billet path for movement toward and away from the billet, a pair of vertically extended cam plates for backing up the respective rolls, said plates vertically fixed in said housing and horizontally shiftably mounted for varying horizontal spacing between said rolls, and respective means supported between each said cam plate and the housing for adjusting the working spacing and releasing the rolls; the last said means including a pair of wedge blocks having complimentarily sloped cooperating contact faces, said blocks

of each pair respectively engaging the back of a cam plate and an inner wall of the housing, means for shifting a first of said blocks in a vertical plane to a selected position to predetermine a working spacing for the rolls, and means for quickly retracting and advancing the second wedge block from and into wedging engagement relative to the first, as the housing approaches the bottom of a downward stroke and the top of an upward return stroke respectively; said cam plates having like roll camming faces including respective sloped lower surfaces mutually upwardly convergent and respective substantially vertically straight mutually parallel upper surfaces.

6. A mill for the continuous conversion of metal into a rolled form from molten metal comprising: means for producing a vertically descending hot billet directly from molten metal, constant speed tandem pinch roll means engaging said billet below the first said means to determine a delivery rate of said billet, a rigid frame and a housing mounted and guided thereon for vertical reciprocation, means for reciprocating the housing, a roll carriage vertically guided in said housing with said billet extending therethrough, vertical racks on the frame and carriage and gear means meshing with said racks for reciprocating the carriage in lagging relation to the housing, a pair of horizontally spaced horizontal rolls mounted in said carriage on opposite sides of the billet path for movement toward and away from the billet, a pair of vertically extended cam plates for backing up the respective rolls, said plates vertically fixed in said housing and shiftably mounted for varying horizontal spacing between the rolls, means biasing the rolls away from each other against cam surfaces on the respective cam plates, and respective means supported between each said cam plate and the housing for adjusting the working spacing and releasing the rolls; the last said means including a pair of cooperating wedge blocks having faces in contact with each other, said blocks of each pair respectively engaging the back of a cam plate and an inner wall of the housing, means for shifting a first of said blocks in a vertical plane to a selected position to predetermine a working spacing for the rolls, and means for quickly retracting and advancing the second wedge block in a vertical plane from and into wedging engagement relative to the first, as the housing approaches the bottom of a downward stroke and the top of an upward return stroke respectively; said cam plates having like roll camming faces including respective sloped lower surfaces mutually upwardly convergent and respective substantially vertically straight mutually parallel upper surfaces.

7. A mill for the continuous conversion of metal into a rolled form from molten metal comprising: means for producing a vertically descending billet directly from molten metal, constant speed tandem pinch roll means engaging said billet below the first said means to determine a feed rate of said billet, a rigid frame and a housing mounted and guided thereon for vertical reciprocation below the pinch roll means, power driven means for reciprocating the housing, a roll carriage supported and guided in said housing for vertical reciprocation along a said billet extending therethrough, cooperating means on the frame and carriage for reciprocating the carriage in lagging relation to the housing, a pair of horizontally spaced horizontal rolls horizontally shiftably mounted in but vertically fixed relative to said carriage on opposite sides of the billet path for movement toward and away from the billet, a pair of variably spaceable vertically extended roll backing cam plates mounted in said housing, and means supported in the housing and acting on the cam plates for establishing a downward stroke working spacing of the plates and for releasing the plates and thereby the rolls as the housing approaches the top of an upward return stroke and the bottom of a downward working stroke respectively; said cam plates having like roll camming faces including respectively sloped lower surfaces mutually upwardly convergent to respective sub-

13

stantially vertically straight mutually parallel upper surfaces.
